United States Patent Office

Des. 179,629
Patented Feb. 5, 1957

179,629

HELICOPTER

Jay Robert Duppstadt, Arlington, and Luell Graham,
Fort Worth, Tex., assignors to Bell Aircraft Corpora-
tion, Wheatfield, N. Y.

Application December 2, 1955, Serial No. 39,129

Term of patent 14 years

(Cl. D71—1)

Fig. 1 is a side elevational view of a helicopter showing our new design;

Fig. 2 is a top plan view thereof; and

Fig. 3 is a front plan view thereof.

The side of the helicopter not shown in the drawing is identical in appearance with the side thereof shown in Fig. 1.

We claim:

The ornamental design for a helicopter, as shown and described.
